EPPA H. RYON, OF WALTHAM, AND WILLIAM W. ROBERTSON, OF WORCESTER, MASSACHUSETTS, ASSIGNORS TO CROMPTON & KNOWLES LOOM WORKS, OF WORCESTER, MASSACHUSETTS, A CORPORATION OF MASSACHUSETTS.

SHED-FORMING MECHANISM FOR JACQUARD LOOMS.

Application filed June 4, 1923. Serial No. 643,179.

This invention relates to looms of the Jacquard type and particularly to means for moving and positioning the heddle cord lifter board or comber board in such looms.

5 It is the object of our invention to improve and simplify the construction of such mechanism, reducing the number of parts and providing for convenient adjustment and modification of the operation thereof.

10 With this general object in view, our invention in its preferred form includes the provision of a lifting frame for a comber board, together with means for giving the board or portions thereof a more limited 15 movement than the movement of the lifting frame itself.

Our invention further relates to arrangements and combinations of parts which will be hereinafter described and more particularly pointed out in the appended claims.

A preferred form of the invention is shown in the drawings, in which

Fig. 1 is a sectional side elevation of a loom having our improved mechanism applied thereto;

Fig. 2 is a transverse sectional elevation of our improved shed forming mechanism;

Fig. 3 is a view similar to Fig. 2 but showing the parts in a different position;

30 Fig. 4 is a partial plan view of the lifting frame and comber board;

Fig. 5 is a partial perspective view of the parts shown in Fig. 4, and

35 Figs. 6 and 7 are detail views illustrating the formation of the shed by our improved mechanism.

Referring particularly to Fig. 1, we have indicated parts of a loom of a usual commercial type, including a loom frame 10, a lay 11 mounted on swords 12, a reed 13, a crankshaft 14, toggle members 15 for oscillating the lay, harnesses 16 for the binder warps B and B' and for the stuffer warp S, and the usual heddle cords 17 for the pile warps P. A bottom or cam shaft 18 carries cams 19 engaging cam levers 20 which are connected through rods or links 21 to lifter lever 22. The levers 22 and additional levers 23 are mounted in bearing frames or brackets 24 at the top of the loom and actuate the shed forming mechanism to be described.

45 The levers 23 are actuated from the levers 22 by links 25 and the centers are so chosen

that the movement of the left hand end of each lever 23 as viewed in Fig. 1 will be about one half of the movement of the corresponding end of the associated lever 22. The levers 22 are pivotally connected by adjustable links 26 to the ends of an upper 50 lifter frame 27 having bars 28 by which the indicated Jacquard wires 29 may be raised to form the pattern on the face of the fabric.

The frame 27 is guided vertically by studs 30 positioned in cam slots 31 (Fig. 3) and is thus given an additional angular or tilting movement so that the wires more remote from the reed will be raised to a higher elevation, thus bringing all of the raised pile 55 warps in the same inclined plane or shed.

The levers 22 are connected by yokes or forks 33 (Fig. 5) to a lower lifter frame 34 vertically slidable upon a fixed stand 35 which also supports the upper lifter frame. 75 The comber board 36 or a holder 36^a therefor is pivoted on one edge at 37 to the vertically movable frame 34 and at its opposite edge is provided with adjustable stop screws 38 adapted to engage the upper face of a side 80 bar 39 forming a part of the lower lifter frame 34.

By adjusting the screws 38 the comber board 36 may be adjusted at any desired angle to the frame 34 and will be held at the 85 adjusted angle when the frame 34 is in raised position. As the frame is lowered, however, the depending projections 40 of the comber board holder 36^a engage adjustable stop screws 41 on the fixed stand 35. 90 The travel of the front edge of the board 36 is thus limited and may be made substantially less than the travel of the lifter frame 34.

In other words, the pivoted connection between the board holder 36^a and the frame 95 34, together with the use of the stop screws 38 and 41, permits a certain definite amount of lost motion for one edge portion of the board relative to the frame.

With this construction the comber board 100 in its raised or mid-position may be substantially level so that the pile warps P will be disposed in a substantially horizontal plane as indicated in Fig. 7, while at the same time the comber board, when in the lowered position shown in Fig. 2 will position the pile warps in the approximately uniform inclined relation shown in Fig. 6. By adjust-

ing the screws 38 and 41 the exact angle at either end of the path of movement may be varied and adjusted as desired. It will be understood that the shed opening is increased 5 or decreased by decreasing or increasing the amount of lost motion for the comber board, and by varying the angle of the comber board, the angle of the corresponding portion of the warp shed may be similarly varied. We are thus able to change either the amount or the angle of shed opening to suit varying conditions of operation.

We have thus provided exceedingly simple 15 mechanism in which a lost motion connection is provided between the comber board and its lifter frame and in which the amount of lost motion and the final position of the board at both ends of its path of travel may be very conveniently adjusted.

20 Having thus described our invention and the advantages thereof, we do not wish to be limited to the details herein disclosed otherwise than as set forth in the claims but what we claim is:—

25 1. In a Jacquard loom, in combination, a shed forming mechanism, a lifter frame positively raised by said mechanism, a comber board mounted on said frame and angularly movable relatively thereto, means to determine the angle of said board relative to said frame when raised by said frame, and additional means to determine the angle of said board when in lowered position.

30 2. In a Jacquard loom, in combination, a shed forming mechanism, a lifter frame positively raised by said mechanism, a comber board mounted on said frame and angularly movable relatively thereto, means to adjust the angle of said board relative to said frame when raised by said frame, and additional means to adjust the angle of said board when in lowered position.

35 3. In a Jacquard loom, in combination, a shed forming mechanism, a lifter frame positively raised by said mechanism, a comber board mounted on said frame and angularly movable relatively thereto, stops on said frame to engage and angularly position said board as the frame is raised, and additional fixed stops to engage and angularly position said board when said board is in lowered position.

40 4. In a Jacquard loom, in combination, a stand, a frame vertically movable on said stand, a comber board, and connections between said board and frame to permit lost motion of one edge portion of said board relative to said frame as said board is raised thereby.

45 5. In a Jacquard loom, in combination, a stand, a frame vertically movable on said stand, a comber board, positive connections between one edge portion of said board and

said frame, and a lost motion connection between the other edge portion of said board and said frame, whereby the angle of said board relative to said frame will be varied within the vertical movement thereof. 65

6. In a Jacquard loom, in combination, a stand, an upper lifter frame, a lower lifter frame, a comber board movably mounted in said lower frame, means to positively move said frames, and means to limit movement of said comber board with said lower frame. 70

7. In a Jacquard loom, in combination, a stand, an upper lifter frame, a lower lifter frame, a comber board movably mounted in said lower frame, means to give said upper lifter frame a positive combined vertical and angular movement, means to give said lower frame a positive vertical movement, and means to change the angular relation of said comber board to said lower frame. 75

8. In a Jacquard loom, in combination, a stand, an upper lifter frame, a lower lifter frame, a comber board movably mounted in said lower frame, and a single operating means effective to give said upper lifter frame a combined vertical and angular movement, and said lower frame a vertical 80 movement of reduced amount. 85

9. In a Jacquard loom, a stand, a comber board angularly movable with respect to the stand, means to raise and lower the comber board, and stops cooperating with the comber board to determine the angular position thereof relatively to the stand as said comber board is raised and lowered by said means. 95

10. In a Jacquard loom, a stand, a comber board angularly movable with respect to the stand, means to raise and lower the comber board, a movable stop to be operatively related to the comber board when the latter is raised to determine the angular position thereof relatively to the stand, and a fixed stop to be operatively related to the comber board when the latter is lowered by said means to determine the angular position thereof relatively to the stand. 100 105

11. In a Jacquard loom, a stand, a comber board angularly movable with respect to the stand, means to raise and lower the comber board, a movable stop to be operatively related to the comber board when the latter moves in one direction to determine one angular position thereof relatively to the stand, and a fixed stop to be operatively related to the comber board when the latter moves in the opposite direction to determine another angular position thereof relatively to the stand. 115 120

In testimony whereof we have hereunto affixed our signatures.

EPPA H. RYON.

WILLIAM W. ROBERTSON.
